UNITED STATES PATENT OFFICE.

JOHAN A. WEINGART, OF NEW YORK, N. Y.

STENOGRAFHER'S PRACTICE DEVICE.

1,192,025.

Specification of Letters Patent. Patented July 25, 1916.

Application filed February 23, 1912. Serial No. 679,470.

To all whom it may concern:

Be it known that I, JOHAN A. WEINGART, a citizen of the United States, residing at No. 469 West One Hundred and Sixty-fourth 5 street, New York city, New York, have invented certain new and useful Improvements in Stenographers' Practice Devices; and I do hereby declare the following to be a full, clear, and exact description of the 10 invention, such as will enable others skilled in the art to which it appertains to make and use the same.

The purpose of the invention is to provide a device which, in the hands of a person 15 learning or practising stenography, will be of service in assisting him to acquire increased speed and accuracy.

To this end the invention comprises a device capable of presenting to view the successive 20 lines of a manuscript or "copy" at a speed which does not substantially exceed or fall below the maximum speed at which the user is able to transcribe, thus serving to urge him to his best speed without lagging or omission. At the same time the matter 25 to be transcribed is presented in such a way that the user will see at once the word he is to transcribe and the stenographic sign which he employs to indicate that word, so that the word and the sign will become associated 30 with one another in his mind.

The device, broadly considered, comprises a manuscript-holder adapted to receive a typewritten or other copy of the matter 35 which has been selected as suitable for practice work, the holder being provided with a sight-opening or the like corresponding in length to the length of the typewritten lines, and preferably arranged to expose but a single line, together with appropriate 40 means for presenting the successive lines of the manuscript at the sight-opening. In working up my invention into practical form I have embodied it in such a structure 45 that this broad idea is associated with more specific features, the purpose of which is to increase the utility of the device by making it convenient to handle, by rendering it possible to quickly change the manuscript held by it, and particularly by so arranging the 50 parts that when the device is in the hand of the user the manuscript may be advanced by drawing the holder toward the user with slight pressure along a flat surface, such as the stenographer's note-book or table, and 55 that the exposed line of manuscript will be

in close proximity to the flat surface so that the stenographer will see in close proximity the word he is to transcribe, and the stenographic sign which he employs to indicate 60 that word. This preferred form of the invention is illustrated in the accompanying drawings, in which—

Figure 1 shows the device in elevation with the cover partly broken away; Fig. 2 65 is a cross-section; and Fig. 3 is a detail showing the automatic stop and one of the terminal plates which support the feed roller.

The manuscript holder is shown as a comparatively thin rectangular box-like frame having a back 1, sides 2 and an upper end strip 3, the front of the holder being closed by the cover 4 and plate 5. Adjustably mounted on the end strip 3 is a spring roller-support comprising the bent spring 6 carried by the screw 7 which passes through the end strip 3 and is provided with the thumb-nut 8 by which the effective tension of the spring may be varied. The spring 6 carries a wire yoke 9 having its two ends bent to form two downwardly extending hooks 10 adapted to receive the ends of the shaft of one of the manuscript-carrying rolls 11. The lower end of the frame is open and below it the other carrying roller 12 is supported by the terminal plates 13 which are notched at their lower extremities to receive the shaft 14 of the roll 12. These terminal plates are identical in form and are preferably made of bent metal having their front edges flush at their upper portions with the cover 4 and projecting somewhat at their lower portions, as shown in Figs. 2 and 3, to receive the ends 15 of the plate 5. The rear edges of the plates 13 are turned under as indicated in Fig. 2 to lie at one portion (indicated at 16) against the back surface of the back plate of the frame, and at another portion (indicated at 17) against one 100 of the side strips 2 and immediately beneath the end of the back 1. The end of the back 1 has a straight edge, and as a result of the construction just described the terminal plates 13 may be made to embrace the 105 lower portion of the frame and the turned-over portions 17 may be brought up against the straight edge so that when the terminal plates 13 are screwed in place by the screws 24 the roller 12 and the lower straight edge 110 of the plate 5, which plate is carried by the terminal plates 13, will always be in aline-

ment. The end of the shaft 14 carries a star-wheel 18 engaged by a spring pawl 19 which is secured to one of the ends 15 of the plate 5 by means of the screw 20 and thumb-nut 21. The two rolls, which are preferably covered by a rubber composition as indicated in Fig. 2, are thus adapted to carry an endless band of manuscript, and in commerce a number of these bands will be made up in proper form to be sold with the holder.

It will be understood that the notches of the star-wheel 18 will be so spaced with relation to the diameter of the shaft 12 and the spacing of the lines on the manuscript that an advance of the star-wheel from one notch to the next will advance the manuscript a sufficient distance to present the next line of writing. In the preferred form of the invention this advancement is accomplished by means of the milled pinions 23 of the shaft 14, which pinions are adapted, by pressure engagement with a flat surface such as the user's note-book or table, to turn the roll and advance the copy, such advance being governed by the star-wheel 18. If the lines of the manuscript were written in the ordinary way the pinions 23 would have to be turned by a movement on the flat surface away from the user to present the lines of the manuscript in succession, and though such an arrangement is entirely feasible, I greatly prefer the arrangement illustrated in the drawings in which the lines of the manuscript are written in reverse order so that by drawing the holder toward the user over the flat surface the lines of the manuscript will be presented in succession. Not only is such a movement the most natural one, but it enables the user, without lifting the device from the flat surface, to follow along with the holder as he advances down the page of his note-book with his stenographic notes, so that the line to be copied is always presented in close proximity to the line of notes which he is writing.

It will further be understood that when the manuscript in the holder is to be changed it is only necessary to snap the ends of shaft of the roll 11 out of the hooks 10, withdraw the roll 11, and then pull out the manuscript with the roll 12, from the lower end of the holder. Whereupon the manuscript may be removed from the roller 12, replaced by another manuscript, and the whole again inserted in the frame, where the manuscript will be held under tension by the spring 6.

Although I have thus illustrated and described the preferred form of my invention embodying the several advantageous features above indicated, nevertheless it will be understood that the invention may be embodied, with all or less than all of these advantageous features, in many different

forms. In fact it is, so far as I am aware, broadly new to provide for the purpose indicated a manuscript-holder having means for exposing in succession the lines of the manuscript, and the claims appended hereto should be correspondingly interpreted.

Having thus described my invention, what I claim is:

1. In a device of the character described, in combination, a frame, a manuscript supported therein, an element movably mounted upon said frame and in engagement with the supporting surface, when the frame is supported upon a surface in its normal position of use, said frame having a sight opening to expose a line of the manuscript, said element being moved upon movement of the frame along the surface upon which it is supported, and mechanism for moving the manuscript as the element is moved, to expose successive lines of the manuscript through the sight opening.

2. In a device of the character described, in combination, a frame, a manuscript supported therein, an element movably mounted upon said frame and in engagement with the supporting surface, when the frame is supported upon a surface in its normal position of use, said frame having a sight opening in the vicinity of the element to expose a line of the manuscript, said element being moved upon movement of the frame along the surface upon which it is supported, and mechanism for moving the manuscript as the element is moved, to expose successive lines of the manuscript through the sight opening.

3. In a device of the character described, a pair of rolls, spring tensioning means for drawing the rolls apart, an endless band of manuscript passing over said rolls with entries thereon written in reverse order of reading, a supporting frame for said rolls inclosing said manuscript except for a sight opening at the lower portion of the frame, and friction wheels carried by the lower roll and protruding at the lower portion of the frame for contact with a flat surface along which the device may be moved progressively while supported in the hand of the operator; substantially as described.

4. In a device of the character described, the combination of a pair of rolls, a frame furnishing bearings for the lower roll and carrying a spring for yieldingly supporting the upper roll to draw said rolls apart, an endless band of manuscript passing over said rolls and capable of advancement upward across the fronts of said rolls, and feed mechanism for advancing the manuscript by equal steps corresponding to the distance between successive lines thereon, said feed mechanism comprising rotating elements protruding at the lower portion of said frame for frictional engagement with a sur-

face over which said frame may be moved while supported by the hand of the operator, said feed mechanism also including a star wheel and spring detent engaging therewith 5 to arrest the manuscript in its successive positions; substantially as described.

5. In a device of the character described, in combination, a frame, a manuscript supported therein and having the lines thereof 10 written in reverse order of reading, an element movably mounted upon said frame and in engagement with the supporting surface, when the frame is supported upon a surface in its normal position of use, said frame having a sight opening to expose a line of the 15 manuscript, said element being moved upon movement of the frame along the surface upon which it is supported, and mechanism for moving the manuscript as the element is 20 moved, to expose successive lines of the manuscript through the sight opening.

6. A stenographer's practice device comprising a manuscript holder, an inclosure therefor of a shape to be held conveniently 25 by the stenographer in one hand in proximity to the surface upon which he is inscribing stenographic notes with the other hand, a sight opening in the said inclosure, and mechanism actuatable by the pressure 30 upon, and movement of the stenographer's hand so holding the device over the surface to progressively advance the manuscript to expose successive lines thereof at the sight opening, whereby the stenographer may 35 keep the words to be copied in immediate proximity to the stenographic signs which he makes to represent them, and may conveniently advance the copy to the sight opening.

40 7. In a device of the character described, a rectangular box-like covered frame open at one end, a feed roll supported in exposed position, at the open end, a spring-yoke within

the frame, a tensioning roll supported by the yoke, a strip of manuscript on the rolls with 45 the lines thereof written in reverse order of reading, and a protruding friction driving element on the feed roll positioned for frictional engagement with a flat surface to advance the manuscript.

50 8. In a device of the character described, a rectangular box-like covered frame open at one end, a feed roll supported in exposed position at the open end, a spring yoke within the frame, a tensioning roll supported by 55 the yoke, a strip of manuscript on the rolls with the lines thereof written in reverse order of reading, a protruding friction driving element on the feed roll positioned for frictional engagement with a flat surface to advance 60 the manuscript, and an automatic stop for arresting the manuscript in such position as to expose successive lines thereof in close proximity to such surface; substantially as described.

65 9. In a device of the character described, the combination of a pair of rolls, an endless manuscript carried thereby, a supporting frame for said rolls having side members and a back, the lower edge of said back 70 forming a straight edge, and terminal plates embracing the side members of the frame, and having portions seating against the straight edge of the back, said plates having receiving sockets for the lowermost feed roll, 75 and a cover plate carried by said terminal plates and having a straight edge near the lower portion of the frame adjacent to which edge the manuscript becomes progressively visible when shifted on said rollers.

80 In testimony whereof I affix my signature, in presence of two witnesses.
